UNITED STATES PATENT OFFICE.

BARTON E. KINGMAN, OF YONKERS, NEW YORK.

DESIGN FOR TAPESTRY CLOTH.

SPECIFICATION forming part of Design No. 16,926, dated October 5, 1886.

Application filed August 13, 1886. Serial No. 210,830. Term of patent 3½ years.

To all whom it may concern:

Be it known that I, BARTON E. KINGMAN, of Yonkers, in the county of Westchester and State of New York, have invented and produced a new and original Design for Tapestry Cloths, of which the following is a specification.

Reference is to be had to the accompanying photograph, forming a part thereof.

10 The leading feature of my design consists of a ground showing alternate ribs of different colors and figures in different colors thrown on the ground or outlined by the parallel ribs.

15 A represents the ground of the tapestry hanging, and B B' B'' the figures. The ground A shows parallel ribs *a a*, two in number, of dark color, and alternating with these the parallel ribs *b b*, two in number, of light color. The figure B is pyramidal in general outline, 20 with many projections, *c c*, between which the parallel ribs *a a* and *b b* appear, as at *d*. The body of the figure B is of a plain solid color, except in the center, where the ribs *a a* and *b b* also appear. Surrounding the figure is a 25 solid border, *f*. The figure B' is funnel-

shaped, and shows the ribbed portion *a a* and *b b*, and the main body of the figure is made up of parallel ribs of different colors. The figure B'' is essentially diamond-shaped, with a right-angled arm. The body of the figure shows, principally, parallel ribs *a a b b*, of different colors, so that the whole surface presents to the eye a ribbed effect or surface combined with the outlines and bodies of figures, with borders, which give the ground a raised 35 appearance.

Having thus fully described my invention, I claim as new and desire to secure by Letters Patent—

30 The design for tapestry cloth herein shown and described, the same consisting of a ground showing parallel alternate ribs of different colors combined with variegated figures of different colors and shapes, and separated from the ground by borders *f*.

BARTON E. KINGMAN.
